(57) **CLAIM**

The ornamental design for a pasta maker as shown and described.

DESCRIPTION

FIG. 1 is a perspective view of a first embodiment of a pasta maker showing my new design;

FIG. 2 is front view of the pasta maker shown in FIG. 1;

FIG. 3 is rear view of the pasta maker shown in FIG. 1;

FIG. 4 is a left-side view of the pasta maker shown in FIG. 1;

FIG. 5 is a right-side view of the pasta maker shown in FIG. 1;

FIG. 6 is a top view of the pasta maker shown in FIG. 1;

FIG. 7 is a bottom view of the pasta maker shown in FIG. 1;

FIG. 8 is a perspective view of a second embodiment of a pasta maker showing my new design;

FIG. 9 is front view of the pasta maker shown in FIG. 8;

FIG. 10 is rear view of the pasta maker shown in FIG. 8;

FIG. 11 is a left-side view of the pasta maker shown in FIG. 8;

FIG. 12 is a right-side view of the pasta maker shown in FIG. 8;

FIG. 13 is a top view of the pasta maker shown in FIG. 8; and,

FIG. 14 is a bottom view of the pasta maker shown in FIG. 8.

The broken-lines show portions of the pasta maker and form no part of the claimed design.

1 Claim, 14 Drawing Sheets
